UNITED STATES PATENT OFFICE.

GEORGE H. LANG, OF BOSTON, MASSACHUSETTS.

LEATHER-MARKING MACHINE.

1,065,257.

Specification of Letters Patent. Patented June 17, 1913.

Application filed June 28, 1909. Serial No. 504,668.

To all whom it may concern:

Be it known that I, GEORGE H. LANG, a citizen of the United States, residing at Boston, county of Suffolk, and State of Massachusetts, have invented an Improvement in Leather-Marking Machines, of which the following description, in connection with the accompanying drawing, is a specification, like letters on the drawing representing 10 like parts.

This invention relates to a machine for marking leather and particularly to a machine for marking on the soles of shoes characters indicating the size, style, case 15 number, etc. I wish it understood, however, that my invention may be applied to other uses than marking characters on the soles of shoes as a machine embodying the invention may be useful in marking characters on 20 leather or other material.

The objects of the invention are to provide a means for heating the type to provide a novel construction whereby the size and half sizes can be readily marked, and to 25 provide a novel support for the soles so that the size and case number or other distinguishing mark can be accurately applied at two different portions of the leather at two successive operations.

Still other objects of my invention are to improve generally this type of machine, all as will be more fully hereinafter described and then pointed out in the appended claims.

In the drawings, wherein I have illustrated one embodiment of my invention, Figure 1 is a side view of a machine embodying my invention with a portion broken out to better show the construction; Fig. 2 is a front view of the printing head; Fig. 3 is an enlarged section through the platen or bed on the line $x-x$, Fig. 1; Fig. 4 is a section through the printing head on the line $y-y$, Fig. 7; Fig. 5 is a detail of the means for advancing the type-disk bearing the unit 40 digits; Fig. 6 is a plan view of the bed or platen; Fig. 7 is a section on substantially the line $a-a$, Fig. 4; Fig. 8 is a view of a shoe sole after the size and case number have been imprinted thereon.

The machine herein illustrated is in many ways similar in construction to the printing machines shown in my two patents No. 864,790, dated September 7, 1907, and No. 877,653, dated January 28, 1908.

The printing head is designated generally by 50 and it carries the type-disks 4, 4^a, 4^b, 4^c,

etc. It is mounted on an arm 5 which is pivoted at 7 to the frame 6 and which is given a vibrating motion by means of a crank disk 8 which is connected to the end 60 of the arm by a link 9. The crank disk is driven by means of a gear 10 which in turn meshes with and is driven by a pinion 11 on a driving shaft 12, and a suitable clutch (not shown) which is operated by a rock-shaft 13 is employed to clutch the pinion to or disengage it from the driving shaft 12. The rotation of the crank disk 8 will 70 vibrate the arm 5 and cause the printing head with the type-disks 4 to rise and fall, as will be obvious. The type-disks are alined during the downward movement of the printing head by an aliner 14 which enters the V-shaped notches 15 formed between the type 75 16 on the disks. The parts thus far described are or may be all as shown in my aforesaid patents and do not form any part of the present invention.

The type disks may be adjusted or set by any suitable mechanism. In the embodiment herein shown a setting mechanism is employed that is somewhat similar to that shown in my above-mentioned patents, that is, each type-disk has rigid therewith a pinion 17 which meshes with teeth 80 18 on a setting disk 21 that is loosely mounted on a rod 19 sustained by the head 3. Each setting disk 21 has rigid therewith a handle 20 by which the corresponding type-disk may be adjusted to 85 bring any type into position to be impressed on the work. Each setting disk 21 has formed on the exposed part thereof characters 22 corresponding to the characters on the type-disk, and these characters 22 are 90 so arranged that the character which occupies a position adjacent the gage 23 indicates the character on the type-disk which is in position for being impressed on the work. Each setting disk 21 is provided 95 with notches 24 and a spring-pressed pivoted finger 25 is associated with each disk to act as a friction lock for holding the disk in its adjusted position. Each finger 25 is 100 preferably provided with a roll 26 at its 105 end which drops into the various notches 24 as the disks 21 are turned, and the spring 27 which acts on each finger is strong enough so that when the roll occupies any notch, as shown in Fig. 4, the disk 21 will be frictionally held from movement. The disk can be 110 readily adjusted, however, by applying a

little force to the handle 20. This manner of adjusting the type-disks is very similar to that shown in my aforesaid patents. As stated above one of the objects of the invention is to provide novel means for heating the type, so that the hot type may be used for burning the impression in leather if it is desired to make an impression without the use of ink. It is possible, however, to use this feature of my invention in connection with machines that are provided with means for printing an impression with ink, and such heating of the type would then be of advantage in case the ink was of such a character that a more lasting impression could be made with heated type than if the type were cold.

In order to heat the type disks 4 I have in this embodiment of my invention mounted them loosely upon a burner tube 30 and each type-disk is provided with a plurality of radial burner openings or passages 31 which terminate at the periphery of the disk at points between the various type 16. The burner tube 30 is provided with apertures 32 which are adapted to communicate with the burner openings 31 of the disks which terminate at the lower side of the disk. I have herein shown the burner tube 30 as having a set of three apertures 32 for each of the type-disks, said apertures being situated on the under side of the tube so that each set of apertures registers with the three ports or burner openings 31 of the corresponding type-disk that are situated on the under side of said disk. The burner tube 30 is arranged to be connected to a source of gas supply so that gas will be delivered to said tube 30 and from the tube to the burner openings 31, and thus a heating flame may be maintained which is sufficient to keep the type hot. I have herein shown the burner tube 30 as connected at one end to a mixing pipe 34 provided with apertures 35 for the admission of air, and said pipe 34 being connected by a flexible pipe 36 to a source of gas supply. The burner tube 30 is non-rotary, but in every position of the rotary type disks some of the burner openings 31 therein will register with the ports 32 in the burner tube, and thus no matter what position the type-disks may occupy, there will always be a sufficient flame maintained to keep the type hot enough to burn an impression in the leather or other work.

While it is possible to use the mechanism thus far described for impressing or burning characters on any work, yet the printing head I have herein shown is especially designed for printing the size and case number on the soles of shoes. In the present embodiment of my invention I arrange the type-disks in two groups, one of which is adapted to imprint the size of the shoe on the sole, and the other of which is adapted

to imprint the case number. The type-disks for printing the size (that is both the length and width size) are grouped at *c*, while the type-disks for printing the case number are grouped at *d*. This arrangement, however, is not essential to my invention, as it is only one of a number of possible arrangements. The type-disks for printing the size of the shoe are formed with both figures and letters, and I also employ an additional type-disk or half-size marker adapted to print a mark indicating the half size. As herein shown, I have illustrated two type-disks 4^a having the digits formed thereon, other type-disks 4^b having the letters of the alphabet thereon, and another type-disk 4^c having the characters to designate the half size thereon and which will be referred to as the half-size marker. There are several ways in which shoe manufacturers designate the half size. The most common ways are by using either one of the following characters: "1/2", "5", "—". According to the first method a 6 shoe and a 6-1/2 shoe would be designated by the character "6" and "6-1/2"; according to the second method by "60" and "65"; and according to the third method by "6" and "6—". In order to use any one of these three methods for indicating the half size, I have placed on the half-size marker 4^c type to imprint the following characters: "1/2", "0", "5", and "—", and the same characters are shown on the disk 21 corresponding to the half-size marker 4^c, as will be observed from Fig. 2. I will preferably arrange a blank type or blank space on the half-size marker adjacent to the "1/2" character, and another blank space adjacent to the "—" character.

For changing the half-size marker 4^c so as to indicate either the size or the half size I have shown an actuator 50 which sets between the disk 21 bearing the half size characters and the adjacent disk carrying the unit digits, and is forked at its lower end to straddle the shaft or rod 19, as clearly seen in dotted lines Fig. 4. This actuator is provided with the handle 51 by which it may be manipulated, and it carries a projection 52 that is adapted to set into a deep notch 53 formed in the periphery of that disk 21 which corresponds to the half-size marker 4^c. This actuator 50 is provided with a slot 54 through which extends a rod 55 carried by the printing head, said rod acting as a means to limit the oscillating movement of the actuator. The movement of the actuator permitted by the rod 55 and slot 54 is just sufficient to turn the disk 4^c so as to bring the half size character into and out of operative position. The disk 21 bearing the half size marks is provided with three deep notches 53 into any one of which the finger 52 may be inserted according to the particular type of half size character which

it is desired to use. The slot 54 is provided with the enlarged portion 56 which permits the actuator to be lifted sufficiently to withdraw the finger 52 from the deep notch 53, and when in this position the disk 21 can be adjusted so as to bring either one of the other two deep notches 53 into position to receive the finger 52. With this construction the setting of the type to print the size or the half size involves merely a movement of the handle 51 in one direction or the other.

Shoes are usually manufactured by cases and each case contains a plurality of pairs of shoes of different sizes. Very frequently the sizes run consecutively, so that one case, for instance, might have sizes 4, 4-1/2; 5, 5-1/2; 6, 6-1/2; 7, 7-1/2, etc., and the operation of marking the sizes on the soles of the shoes in any case involves resetting the type of the marking machine to mark these successive sizes. In order to facilitate this operation I have provided a novel construction whereby the adjustment of the half-size marker 4^c from the position for marking the half size to that for marking the size will advance by one step the type-disk 4^a having the unit digits thereon, so that by merely reciprocating the handle 51, the type-disks will not only be set for the sizes and half sizes, but the type-disk bearing the unit digits will be advanced step by step to indicate the gradually increasing sizes. I accomplish this by providing the actuator 50 with a pawl 60 which is adapted to engage the disk 21 corresponding to the unit digits type-disk. This pawl 60 is so constructed that during the movement of the handle 51 to the left Fig. 4 it will slide over the surface of the disk 21, but when the handle moves to the right, the nose of the pawl will engage one of the notches 24 in said disk, thereby advancing it one step. It will thus be seen that it is possible to set the disks for different sizes and half sizes merely by operating the handle 51.

The bed or platen on which the shoe soles rest while they are being imprinted is shown at 62. It is yieldingly mounted and has such a position that the type come against the work before the printing head has completed its downward movement, so that during the latter part of the downward movement of the type head the bed moves downwardly therewith. In this way a sufficiently long contact is provided between the type and the work to permit the heated type to properly burn the impression in the work. I have herein shown the platen 62 as provided with a stem 63 which extends through a sleeve 64 carried by the base 65. A spring 66 surrounding the sleeve normally holds the platen in its elevated position but permits it to yield when the type is brought against the work. The up-

ward movement of the platen is limited by the nut 67 which is screw-threaded to the lower end of the stem 63.

The machine herein shown is designed to imprint the size characters and the case number on the sole at two different operations, and in order that these two numbers shall be properly placed with reference to each other, I have provided a gage for the sole which is adapted to maintain it in one position while the size number is being imprinted thereon, and in another position while the case number is being imprinted thereon. The gage is shown at 70 and it is formed with the two surfaces 71 and 72 situated at different distances from the line where the printing takes place. The gage is preferably adjustably mounted on the bed 65 and is held in its adjusted position by a clamping screw 73 which screws into the bed and extends into a slot 74 in the foot 75 of the gage. The platen 62 has associated therewith two side guides 76 and 77 against which the sides of the sole rest during the printing operation. These side guides 76, 77 are adjustably sustained by the platen so that they can be moved toward and from the center thereof to accommodate soles of different widths. One convenient way of thus adjustably mounting them is that herein shown wherein each guide has extending therefrom two guiding pins 78 which slide through apertures formed in wings 79 on the platen. For adjusting the guides I provide the screw 80 which extends through an aperture in the platen and is provided with screw threads 81 that have screw-threaded engagement with the platen and with other screw threads 82 that have screw-threaded engagement with the guide 76. The guide 77 is connected to the end of the screw 81, said screw having a swivel connection with the guide. The screw-threads 82 and 81 are both right hand screw threads, but the screw-thread 82 has double the pitch than the screw-thread 81 has. The screw 80 is provided with the knurled head 83 by which it may be turned. From the above it will be seen that when the screw is turned in one direction said screw will be carried through the platen 62 thereby moving the guide 77 away from the platen but at the same time the guide 76 will be screwed back on the coarse screw threads 82 so that it will move away from the platen at the same speed that the guide 77 does. This construction takes the place of ordinary right and left hand screws for adjusting the guides 77 and 76 simultaneously, and provides a construction which is not only easier to make but which is much less likely to get out of order and which requires much less accurate alinement than a right and left hand screw does.

In the operation of the device the guides

76, 77 will be properly adjusted to accommodate the width of the sole and the sole will be placed on the platen with the end of the heel against the surface 71, and the side of the sole against the guides 77, as shown in dotted lines Fig. 6. The machine will then be started and the size numbers will be imprinted on the sole. The sole is then shifted into the dot and dash position Fig. 6 to bring the heel against the surface 72 and at the next descent of the printing head the case number will be printed on the sole. Since the two surfaces 71 and 72 are out of alinement with each other it will be seen that the case number will be printed in a different position from the size number and the two numbers will appear on the sole, one above the other, as seen in Fig. 8.

20 Having fully described my invention, what I claim as new and desire to secure by Letters Patent is:—

25 1. In a machine for marking leather, the combination with a bed or platen, of a printing head having a plurality of type-disks, each having a burner opening, and a burner pipe having ports communicating with the burner openings.

30 2. In a machine for marking leather, the combination with a bed or platen, of a printing head having a plurality of adjustable type-disks, each having radial burner openings, a burner pipe on which said disks are rotatably mounted and which is provided 35 with ports to deliver gas to the burner openings.

35 3. In a machine for marking leather, the combination with a bed or platen, of a printing head having a plurality of adjustable type-disks, each having radial burner openings, a burner pipe on which said disks are rotatably mounted and which is provided 40 with ports on its under side to deliver gas to those burner openings in the lower half 45 of each type-disk.

40 4. In a machine of the class described, the combination with a shaft, of two disks rotatably mounted thereon, an operating handle interposed between the disks and capable of 50 both an oscillatory and a radial movement and having provision to move one of said disks in both directions as it oscillates, the other disk having notches in its periphery, and a tooth carried by said handle and 55 adapted to engage the notches successively as the handle oscillates thereby to advance said disk step by step.

55 5. In a machine of the class described, the combination with a half-size marker having 60 a half-size printing character thereon, of an adjacent type wheel, two setting disks, one connected to the marker and the other to said type wheel, an operating handle having engagement with the setting disk for the 65 half-size marker by which said disk may be

removed to bring the half-size printing character into printing position and retract it therefrom, and means carried by said handle to engage the other setting disk and move the latter in one direction only.

6. In a machine of the class described, the combination with a half-size marker and an adjacent type wheel, of two setting disks, one connected with the half-size marker and the other with the type wheel, a shaft on 75 which said setting disks are mounted, an actuator interposed between said disks and having a forked end engaging said shaft, means connecting said actuator with one of said disks to move it in both directions, and means connecting said actuator with the other disk to cause it to move in one direction only.

7. In a machine of the class described, the combination with a shaft, of two disks rotatably mounted thereon, an operating handle having a forked portion interposed between said disks and embracing said shaft, each disk having notches in its periphery, a square-faced tooth secured to said handle and engaging the notches of one of said disks, and a beveled tooth connected to the handle and engaging the notches of the other disk.

8. In a machine for marking soles of 95 shoes, the combination with a printing head having adjustable type, of a bed or platen to support the shoe, a screw having a screw-threaded portion of a fine pitch working through a fixed nut, a gage for the edge of 100 the shoe sustained by the end of the screw, said screw having another screw-threaded portion of a coarse pitch, a second gage having screw-threaded engagement with the coarse screw threads.

9. In a machine for marking the soles of 105 shoes, the combination with a platen, of a printing head having two sets of type carrying members situated so that the sole to be printed occupies different positions when 110 being printed on by either of said sets, and a gage to position the shoe sole on the platen, said gage having two gaging surfaces, one adapted to position a sole when one set of type carrying members is printing characters thereon and the other adapted to properly position the sole when the other set of type carrying members is printing thereon.

10. In a machine of the class described 120 the combination with a half-size marker and an adjacent type wheel, of a non-rotatable support on which said marker and wheel are loosely mounted for rotary movement, means to apply heat to the disk and wheel 125 through said non-rotary support, two setting disks, one connected with the half-size marker and the other with the type wheel, a shaft on which said setting disks are mounted, an actuator interposed between 130

said disks and having a forked end engaging said shaft, means connecting said actuator with one of said disks to move it in both directions, and means connecting said actuator with the other disk to cause it to move in one direction only.

In testimony whereof, I have signed my

name to this specification, in the presence of two subscribing witnesses.

GEORGE H. LANG.
